Primary Examiner — Mitchell I. Siegel(74) Attorney, Agent, or Firm — Randy K. Chang(57) CLAIM

The ornamental design for iron golf club head, as shown and described.

DESCRIPTION

FIG. 1 is a perspective view of my new design for an iron golf club head;

FIG. 2 is a back view thereof;

FIG. 3 is a top view thereof;

FIG. 4 is a front view thereof;

FIG. 5 is a bottom sole view thereof;

FIG. 6 is a heel view thereof; and,

FIG. 7 is a toe view thereof.

The broken line showing of grooves on the striking surface is included for the purpose of illustrating and forms no part of the claimed design.
